UNITED STATES PATENT OFFICE.

ARTHUR C. GRIEWANK, OF SAN FRANCISCO, CALIFORNIA, ASSIGNOR OF ONE-HALF TO
EMILE CERF, OF SAN FRANCISCO, CALIFORNIA.

MECHANICALLY-OPERATED FIGURE.

Application filed December 8, 1925. Serial No. 73,961.

This invention relates to mechanical figures and particularly to a moving novelty adapted to simulate a body. It is well known that a moving sign or object attracts much greater attention than a still object, and this attraction is even greater when the object simulates a movable form. It is the primary object of my invention to provide an improved mechanical figure of this type which can be used as an advertising novelty.

It is a further object of my invention to provide a moving mechanical figure which is so constructed as to operate continuously with very little power. In accordance with this object, I preferably pivot the moving members and counterbalance the same in a manner operating the members in a swing-like pendulum action, a small inexpensive motor being provided to intermittently give a moving impulse to the members.

With the above mentioned and other objects in view, my invention consists of the features of construction and operation set forth in the following specification and illustrated in the accompanying drawing. In such drawing annexed hereto and forming a part of this specification, I have illustrated certain specific embodiments of my invention, but it will be understood that the invention can be otherwise embodied and that the drawing is not to be construed as defining or limiting the scope of the invention, the claims appended to the specification being relied upon for that purpose.

Referring to the figures of the drawing:

Figure 1 is a front view of one embodiment of my invention.

Figure 2 is a fragmentary sectional view thereof taken on line 2—2 of Fig. 1.

Figure 3 is a fragmentary view of a slightly modified construction.

In the drawing, 1 indicates the trunk portion of a body supported by a post 2. A pair of arms 3 are pivoted to the body at 4, and these arms are counterweighted at 5 to normally hold the arms in a horizontal position. A pair of legs 6 are pivoted to the body at 7, the legs preferably being jointed at 8 and 9. Counterweights may be provided in the legs at 10 and each foot may be counterweighted at 11.

The head 12 of the body is pivotally supported on two pins 13 carried by extensions 14. The head is counterweighted at 15 to

normally hold the same in an upright position. The eyes 16 are pivoted at 17 and counterweighted at 18. A hat or crown piece of any configuration may be provided on the head. I have shown a small bell 18^a supported thereon by a wire staple 19.

As illustrated, the arms, legs, and head are so counterweighted as to ordinarily hold these parts in their normal positions and to act thereon to aid in keeping the same swinging pendulum-like. I have provided means to act on these parts intermittently to give the same a swinging impulse. As illustrated in Fig. 2, I provide a spring motor 20 on the back of the body member 1. An arm 21 connected to and rotatable around the motor is adapted to contact with the head counterweight 15 and bars 16^a extending from the arms and legs into the path of movement of this arm 21.

The operation of the device is simple, being substantially as follows. The motor being wound by a key 22, slowly rotates the arm 21 in the direction of the arrow. As the arm contacts with the counterweight 15 and bars 16^a, the head, arms, and legs are rocked on their pivots. The counterweights thereof function to keep these members swinging like a pendulum. It will also be noted that as the head rocks forwardly and backwardly, (Figs. 1 and 2) the eyes roll upwardly and downwardly on their pivots. The speed of the arm 21 can be so timed as to give a swinging impulse to the pivoted members, substantially when the same come to the end of their swinging movements. The motor is therefore operated very slowly and one winding thereof will serve to operate the device for a considerable period of time.

It should be understood that the various members can be pivoted in relations other than those shown in the drawing. For example, the head can be pivoted to swing side-wise instead of forwardly and backwardly. I have illustrated such a construction in Fig. 3. The head 23 is pivoted at 24 to a bar 25 connecting the two uprights 26 on the body 27. The head is counterweighted at 28 and also provided with a lug 29 adapted to be engaged by the motor arm 21 to rock the head on its pivot 24. The eyes 30 are pivoted at 31 and counterweighted at 32.

Obviously, the figure comprising the device can be decorated in any manner desired.

For example, in Fig. 1, I have illustrated one hand as holding a flag 33 and the other hand as holding a signal bell 34. The eye balls of the eyes may also have electric bulbs mounted therein if desired. Other novelties can be added to the device as may seem best.

While I have herein referred to my invention as a mechanical figure, I wish it to be clearly understood that the same is capable of such uses as a toy, a scarecrow, as an advertising novelty, etc., and it is intended that the scope of the appended claims shall be such as to include all of such uses.

Having thus described my invention, what I claim is:

1. A mechanical figure comprising the combination of a body, members pivoted to the body to simulate moving parts thereof, means intermittently operating on the members to rock the same about their pivots, a motor for driving the said means, means cooperating with the members to assist in keeping the same rocking pendulum-like, and means supporting the body in a manner permitting free pivotal movement of the said members.

2. A mechanical figure comprising the combination of a body, members pivoted to the body to simulate moving parts thereof, a rotary arm adapted to intermittently engage the members in a manner rocking the same about their pivots, a motor for rotating the arm, counterbalancing weights cooperating with the members to assist in keeping the same rocking pendulum-like, and means supporting the body in a manner permitting free pivotal movement of the said members.

3. A mechanical figure comprising the combination of a body, members pivoted to the body to simulate the arms and head thereof, means intermittently operating on the members to rock the arms and head about their pivots, a motor for driving the said means, means cooperating with the members to assist in keeping the same rocking pendulum-like, and means supporting

the body in a manner permitting free pivotal movement of the said members.

4. A mechanical figure comprising the combination of a body, members pivoted to the body to simulate the arms and legs thereof, means intermittently operating on the members to rock the arms and legs about their pivots, a motor for driving the said means, counterbalancing weights cooperating with the members to assist in keeping the same rocking pendulum-like, and means supporting the body in a manner permitting free pivotal movement of the said members.

5. A mechanical figure comprising the combination of a body, members pivoted to the body to simulate the arms, legs, and head thereof, means intermittently operating on the members to rock the arms, legs and head about their pivots, a motor for driving the said means, means cooperating with the members to assist in keeping the same rocking pendulum-like, and means supporting the body in a manner permitting free pivotal movement of the said members.

6. A mechanical figure comprising the combination of a body, a head pivoted thereto in a manner balancing the weight of the head on the pivot, eyes pivoted to the head, means intermittently operating on the head to rock the same about its pivot, a motor for driving the said means, and counterbalancing weights for causing the eyes to roll on their pivots as the head rocks.

7. A mechanical figure comprising the combination of a body, a head pivoted thereto, eyes pivoted to the head, means intermittently operating on the head to rock the same about its pivot, a motor for driving the said means, a counterbalancing weight cooperating with the head for assisting in keeping the head rocking pendulum-like, and counterbalancing weights for causing the eyes to roll on their pivots as the head rocks.

ARTHUR C. GRIEWANK.
